CARPET SWEeper

Filed March 19, 1926

UNITED STATES PATENT OFFICE

IRA J. OWEN, OF GRAND RAPIDS, MICHIGAN, ASSIGNOR TO BISSELL CARPET SWEEPER COMPANY, OF GRAND RAPIDS, MICHIGAN

CARPET SWEEPER

Application filed March 19, 1926. Serial No. 95,887.

This invention relates to an improved, cheap and simple construction of carpet sweeper adapted to toy size. The structure is available for full size carpet sweepers.

5 The objects of the invention are:

First, to provide improved driving parts and arrangement of the same.

Second, to provide an improved case and assembly support, and reinforce and connection for the bail of the handle.

Third, to provide an improved case and frame construction whereby these parts are retained in effective operative relation.

Fourth, to provide a structure which is especially well adapted to the simple fiber case.

20 Objects pertaining to details and economies of my invention will definitely appear from the detailed description to follow. The invention is clearly defined and pointed out in the claims.

A structure embodying the features of my invention is clearly illustrated in the accompanying drawings forming a part of this 25 application, in which:

Fig. 1 is a side elevation view of a toy carpet sweeper embodying the features of my invention, a part of the handle being broken away.

30 Fig. 2 is an enlarged detail end elevation view with the handle in sections.

Fig. 3 is an enlarged detail sectional view on line 3—3 of Figs. 1, 4 and 2, the floor and brush wheels being in full lines.

35 Fig. 4 is an enlarged detail sectional view on line 4—4 of Figs. 2, 3, 5 and 6 showing details of one of the floor wheels and its axle and its connection and relation to the dust pan and other parts of the structure.

40 Fig. 5 is an enlarged detail sectional view on line 5—5 of Fig. 1, 3 and 4.

Fig. 6 is an enlarged detail sectional elevation view on line 6—6 of Figs. 1 and 4.

45 The parts will be identified by their numerals of reference which are the same in all the views.

1 is the main body of the case having ends 2 suitably slotted at 21 to accommodate the brush spindle. 3 is the brush of usual twisted wire axle form retaining the bristles by

that means. 4 is the brush wheel having a rounded projecting pivot hub 41 at its center to constitute the journal. 5 is the guard, brush and wheel support plate, having a bearing depression 51 at the center for the pivot hub 41 of the brush wheel 4. It is formed of sheet metal and has a flat angular attaching base 52 retained in place by nails 53, the angle 54 projecting over the top of the case end to form a guard and reinforce at that point. A horizontal portion 55 extends outwardly from the end of the case and then downwardly in the offset at 56 to form the floor wheel retainer, the same projecting slightly laterally at 57 and being reinforced at that point by struck up rib portions 57'. These retain the floor wheels against longitudinal displacement and permit them to play freely up and down and laterally into contact with the brush wheel. The plate is perforated at 58 for the bail pivot. The same is a reinforcement for the handle bail pivot bearing which projects therethrough into the end of the case.

75 The dust pan 6 is carried by pivots 61 which are the axles for the floor wheels. These project outwardly at each end through enlarged apertures 22 in the case ends 2 as seen in Figs. 3, 4, and 5, the position of the dust pan being indicated by dotted lines at the right of Fig. 5.

80 The dust pans 6 are rabbeted into a shoulder 62 at their outer edges to engage under the edge of the case. The floor wheels 63 are carried on the axles 61 and are provided with hubs 63' of sufficient size to cover the aperture 22 in the side of the case which insures freedom of movement.

85 It will thus be seen that the floor wheels are connected to and carry directly the dust pan and serve the additional duty as they are pivotal supports for the dust pan. Their movement is limited by the aperture 22 which is sufficiently large to allow the needed play of the parts.

90 A spring 64, see Fig. 6, is folded on itself at the center and projects upwardly into contact with the inside of the top of the case midway of the ends and at the end. The lower end of the spring is turned at right 95 100

angles and forms a pivot at the upper inner corner of the dust pan parallel with the axle.

The spring being put under tension serves to force the inner end of the dust pan down and close the outer edge against the case and tensions the floor wheels in position. When the case is forced down by the action upon the handle in operating the sweeper, it carries the end bar with the brush down into yielding contact with the floor wheels which drives the brush. The floor wheels serve as the support for the dust pan at the same time.

When further stress is applied, enough to cause movement, the entire carpet sweeper case and the brush are forced down against the floor, thus securing the broom action when the carpet sweeper is actuated.

The carpet sweeper is provided with the usual bail handle 7 which is pivoted in apertures at the ends of the case. The pivot projects through aperture 58 in the guard plate 5, as before stated, and there is struck up on the guard plate the angular rib 59 to support the said bail out of contact with the guard plate so that it will swing freely in use. There are outwardly projecting knobs 59' which hold the bail yieldingly in vertical position when at rest.

From this description it will be seen that a very simple structure is produced which is very effective in operation, providing at very small cost a toy carpet sweeper that actually works. The brushes revolve by their hub bearings 41 very readily in the smooth depressions 51 in the center of the support 5. The support 5 retains the parts yieldingly together and serves as a means for preventing the floor wheels sliding off their journals, and insures their very free operation as a consequence, and the ready removal and insertion of the brush.

From what has been described it will be seen that this improved structure provides a strengthening plate at the end which serves as the longitudinal retainer for the floor wheels and as the pivot or journal support for the brush. It also provides a reinforce support for the bail with means for holding it in vertical position when out of use. The structure is very strong and lends itself to very rapid and at the same time nicely finished construction.

While I have shown the case of paper construction, which is held very securely as here shown, the invention is, of course, of wider application, and I desire to claim this feature both specifically and broadly as pointed out.

Having thus described my invention what I claim as new and desire to secure by Letters Patent is:

1. In a carpet sweeper, the combination of a case with slotted ends to removably receive the brush and enlarged apertures for the movement of the floor wheel axles, a rotary

brush with driven wheels therefor with axially projecting pivots, dust pans with straight extended stub axle pins fixed in each end thereof and extending through said enlarged apertures in the case ends, floor wheels journaled on said axle pins, and a guard plate at each end with depression for the said brush pivot and with wheel retainer portions to retain the wheels on the said axles, comprising a flat base part attached to the casing, the said retainer parts being offset in spaced parallel relation to the base part.

2. In a carpet sweeper, the combination of a case with slotted ends to removably receive the brush, a rotary brush with driven wheels therefor with axially projecting pivots, dust pans with straight extended stub axle pins fixed in the ends thereof and extending through the said case ends, floor wheels journaled on said axle pins outside said case ends, and a guard plate at each end with a depression directly engaging the brush pivot and with wheel guard portions for said floor wheels, each comprising a flat base part attached to the casing, the said guard parts being offset in spaced parallel relation to the ends of said sweeper case.

In witness whereof I have hereunto set my hand.

IRA J. OWEN.
